END CAP FOR GOLF CLUB GRIPS

Harold G. Barrett, Wilmette, Ill.

Application November 19, 1931
Serial No. 575,991

4 Claims. (Cl. 273—81)

This invention relates to end caps for golf club grips and the like.

In my copending application, Serial No. 519,943, filed March 4, 1931, I have shown and described an end cap for a golf club grip adapted to secure the end of the grip as well as prevent damage thereto and the resulting fraying and the like, and the cap of the present invention is adapted for similar use. The primary object of this invention is to provide a novel end cap of the foregoing description which may be so secured in position that relative rotation between the cap and the end of the club will be prevented and an object, ancillary to the foregoing, is to provide an end cap embodying a formed portion which may be securely clamped to the end of the club.

Other and further objects will appear hereinafter.

20 In the selected embodiment of my invention illustrated in the accompanying drawing,

Fig. 1 is a fragmentary vertical sectional view illustrating one form of my invention;

25 Fig. 2 is a plan view of the main body portion of my novel cap;

Fig. 3 is a fragmentary vertical sectional view of a modified form of construction; and

30 Fig. 4 is a view similar to Figs. 1 and 3 depicting a further modified form of my invention.

In the accompanying drawing I have fragmentally illustrated a golf club grip of annular cross-section but it is within the purview of my invention to employ a grip of polygonal cross-section and when such a grip is provided the periphery of my novel cap will conform to the periphery of the grip. I have also illustrated my invention in connection with so-called bell-top grips which are of somewhat frusto-conical configuration with the flared end thereof disposed at the outer end of the grip but my invention is not limited to use with grips of this particular shape. The bell-top configuration, in the illustrated embodiment of the invention, is formed on the body member of my improved cap which may be in the nature of an end plug 5 adapted to be inserted into the end of the hollow metal shaft 6 of the club. However, when the invention is used with a wooden shafted club, this configuration will be provided on the upper end of such shaft. The plug 5 and the adjacent portion of the shaft 6 provide the handle of the club whereat the grip is arranged which includes the usual cushion 7. The grip includes a leather strap 8 or the like spirally wound about the handle

with the upper marginal section 9 thereof extending beyond the end of the plug 5. In the embodiment of the invention illustrated in Fig. 1, a conical recess 10 is centrally formed in the end of the plug. My novel cap, indicated 60 as a whole by 11, is preferably made from sheet material. If made of metal the cap will be suitably finished as by polishing or plating. When made of pyroxyline or like material, it may be made of one or more colors or otherwise arranged to increase the aesthetic appearance thereof. The cap may be formed by pressing it into a desired form or it may be spun from a suitably shaped section of the material. The cap includes a main body 12 having a medial 70 portion thereof depressed to provide a recess 13. The medial portion of the bottom of the recess 13 is depressed to provide a frusto-conical portion 14 having an opening at the apex thereof. The frusto-conical portion 14 is 75 adapted to be seated in the conical recess 10 and a wood screw 15 or other suitable securing device is passed through the opening at the apex of the portion 14 and is secured in the end of the plug 5. The securing device preferably includes a tapered head 16 which seats in the frusto-conical portion 14 to tightly clamp it against the wall of the conical recess and thus the cap is tightly clamped in position and usually this clamping will be sufficient to prevent relative movement between the plug 5 and the cap. Under certain conditions it may be desirable to insure against relative rotation between the plug and cap and to such end a lip 17 is struck from the frusto-conical portion 14 80 adjacent the opening therein and which will be fitted into a notch or the like in the conical recess 10 and if desired additional lips, such as 17, may be provided. At the periphery of the main body portion 12 of the cap is a depending flange 18, the free edge of which is chamfered as at 19. The portion of the bottom wall of the recess 13 about the frusto-conical portion 14 is rested on the adjacent end of the plug 5. In installing the cap the marginal section 9 is 85 folded over onto the adjacent end of the plug 5 with the chamfered edge 19 rested on the fold and as the screw 15 clamps the frusto-conical portion 14 in position, the chamfered edge 19 is tightly engaged with the fold in the leather strap 8 whereby the end of the strap is clamped securely. The outer face of the flange 18 is 90 preferably aligned with the outer face of the strap 8 and therefore a smooth end is formed on the handle. The end of the strap is covered 95 on the handle. The end of the strap is covered 100

105

110

by the cap and thus fraying or other damage thereto is prevented. The cap is preferably of pleasing appearance and this may be enhanced by inserting a plug 20, of pyroxyline or other suitable sheet material, in the recess 13 and this plug may be of a blending or contrasting color relative to the main body portion of the cap. The plug is tightly pressed into the recess 14 to prevent displacement and if desired 10 a suitable adhesive may be used to further insure against displacement. If the plug and/or the body portion 12 be of pyroxyline material, a small amount of acetone will be introduced into the recess which by its chemical action on such 15 material will secure the plug in the recess. The plug conceals the end of the securing device 15 and prevents undesired removal or displacement thereof.

The embodiment of the invention illustrated 20 in Fig. 3 is substantially similar to that shown in Fig. 1 but in this instance the depending flange 18' has the free edge thereof tapered as indicated at 19' whereby this edge may be alined with the periphery of the grip and in this instance a recess 21 is provided in the end of the plug 5' into which the portion providing the recess 13 may be extended. It will be noted that the construction illustrated in Fig. 1 affords a clearance between the inner surface of the main 30 body portion 12 and the end of the plug 5 into which the marginal section 9 may be extended. In the arrangement shown in Fig. 3 no such clearance is provided and the marginal portion 35 9 in this instance is effectively clamped throughout its extent between the body portion 12' and the end of the plug 5'.

In the embodiment of the invention illustrated in Fig. 4 the periphery of the cap 12'' is formed in the same manner as the periphery of the 40 cap 12'. In this instance a boss 22 is formed at the medial portion of the end of the plug 5''. In order to provide the recess 13 in this instance it is necessary that the body portion 12'' be bent upwardly whereby the medial portion 45 24 of the main body portion 12'' is disposed in a plane above the periphery thereof. The portion providing the recess 13'' in this instance is rested on the end of the boss 22. In this construction the marginal section 9 rests against the end of 50 the cap 5'' and about the boss 22 and is effectively clamped in this position by the adjacent section of the body portion 12'' of the cap.

The embodiments of the invention illustrated in Figs. 3 and 4 are similar to the embodiment 55 illustrated in Fig. 1 in all respects other than those described.

From the foregoing description it is manifest that I have provided an end cap for golf club grips and the like which securely fastens the 60 ends of such grips. The cap provides a smooth end for the grip and prevents damage thereto. The cap is of pleasing appearance and enhances the aesthetic appearance of not only the grip but of the club as a whole. Since both the cap 65 and its plug may be made from sheet material, economical manufacture is attained.

In the foregoing description I have described selected forms of my invention but it is to be understood that these are capable of variation 70 and modification and may be used for purposes other than that described. I, therefore, do not wish to be limited to the precise details set forth but desire to avail myself of such changes and alterations as fall within the ambit of the 75 following claims.

I claim:

1. In a grip for golf clubs and the like which has a handle having a conical opening in the end thereof, and a strap wound about the periphery thereof and including a portion extending beyond the end of the handle, the combination therewith of a cap adapted to be mounted on the end of the handle and including a recessed portion having a conical portion at the bottom thereof adapted to be disposed in said conical opening, securing means including a clamping portion for forcing said conical portion into clamping engagement with said conical opening to retain said cap on said handle, the portion of said strap extending beyond the end of the handle being folded onto the end of said handle, said cap including a depending peripheral portion embracing said strap at the fold therein to clamp said strap against displacement, said cap having the outer edge thereof alined with the outer surface of the strap to provide a smooth end on the grip, and a plug seated in said recessed portion outwardly of said securing means.

2. In a grip for golf clubs and the like which has a handle having a conical opening in the end thereof, and embodying a notch adjacent the bottom of said conical opening, and a strap wound about the periphery thereof and including a portion extending beyond the end of the handle, the combination therewith of a cap adapted to be mounted on the end of the handle and including a recessed portion having a conical portion at the bottom thereof adapted to be disposed in said conical opening, said conical portion including a depending lip adapted to be seated in said notch, securing means including a clamping portion for forcing said conical portion into clamping engagement with said conical opening to retain said cap on said handle, the portion of said strap extending beyond the end of the handle being folded onto the end of said handle, said cap including a depending peripheral portion embodying a chamfered edge embracing said strap at the fold therein to clamp said strap against displacement, said cap having the outer edge thereof alined with the outer surface of the strap to provide a smooth end on the grip, and a plug seated in said recessed portion outwardly of said securing means.

3. In a grip for golf clubs and the like which has a handle having an opening in the end thereof including a conical portion, and a strap wound about the periphery thereof and including a portion extending beyond the end of the handle, the combination therewith of a cap adapted to be mounted on the end of the handle and including a recessed portion having an outwardly projecting conical section at the bottom thereof, said recessed portion including a part seated in said opening and having the conical section thereof disposed in the conical portion of said opening, securing means including a clamping portion for forcing said conical section into clamping engagement with the conical portion of the opening to retain said cap on said handle, the portion of said strap extending beyond the end of the handle being folded onto the end of said handle, said cap including a depending peripheral portion embracing said strap at the fold therein and having the part thereof intermediate the peripheral portion and the recessed portion engaged with the folded portion of said strap whereby the depending peripheral

portion and intermediate part clamp said strap against the end of said handle, said cap having the outer edge thereof alined with the outer surface of the strap to provide a smooth end on the grip, and a plug seated in said recessed portion outwardly of said securing means.

4. In a grip for golf clubs and the like which has a handle having a conical opening in the end thereof, and a strap wound about the periphery thereof and including a portion extending beyond the end of the handle, the combination therewith of a cap adapted to be mounted on the end of the handle and including a medially located raised portion having a recessed part therein embodying a conical section adapted to be seated in said conical opening, secur-

ing means including a clamping portion for forcing said conical section into clamping engagement with said conical opening to retain said cap on said handle, a portion of said strap extending beyond the end of the handle being folded onto the end of said handle, said cap including a depending peripheral portion having a chamfered edge embracing said strap at the fold therein to clamp said strap against displacement, said cap having the outer edge thereof alined with the outer surface of the strap to provide a smooth end on the grip, and a plug seated in said recessed portion outwardly of said securing means.
